Alfred G. Plimmer
INVENTOR.

BY *Alfred G. Plimmer*
ATTORNEYS.

UNITED STATES PATENT OFFICE.

ALFRED G. PLIMMER, OF CLEVELAND, OHIO, ASSIGNOR TO NATIONAL CARBON COMPANY, INC., A CORPORATION OF NEW YORK.

ELECTRICAL CONNECTION AND METHOD OF FORMING THE SAME.

Application filed March 3, 1926. Serial No. 92,000.

My invention relates to that class of electrical connections which are especially useful in uniting flexible metal conductors, commonly made of copper strands and known as shunts or pigtails, to carbon brushes or blocks adapted for use on electric motors and generators and the like, although my invention may be employed in other connections such, for example, as battery electrodes or contacts for electric switches.

An object of my invention is to provide an improved means for attaching a shunt or pigtail to a brush of the character indicated whereby the brush and shunt may be easily and quickly assembled in a permanent manner and with good electrical contact between the several parts. Another object of my invention is to provide a simple and rapid process of assembling brushes which will reduce the amount of machining, especially countersinking, necessary on the brush.

These and further objects of my invention will be evident from the following description having reference to the annexed drawing in which:

Fig. 1 is a front elevation of a brush and conductor showing one embodiment of my invention;

Fig. 2 is a vertical section on the line 2—2 of Fig. 1;

Fig. 3 is an elevation of the gripping means employed in my invention, the gripping means being shown before deformation;

Figs. 4 and 5 are elevations of two interlocking members which may be substituted for the single gripping member of Fig. 3;

Figs. 6 and 7, 8 and 9, and 10 and 11, show three other pairs of interlocking members which also may be substituted for the single deformable gripping member of Fig. 3;

Figs. 12 and 13, 14 and 15, and 16 and 17, show pairs of non-interlocking members which also may be substituted for the single deformable member;

Fig. 18 is a front elevation of another type of deformable gripping member;

Fig. 19 is a vertical section taken on the line 19—19 of Fig. 18;

Fig. 20 is a plan view of a portion of a brush showing a modified mode of carrying out my invention;

Fig. 21 is a front elevation thereof; and

Fig. 22 is a plan view of the gripping member before deformation.

Heretofore it has been the practice either

to compress the shunt between the gripping member and a portion of the carbon block, which does not give as secure a connection and as low a resistance as that disclosed herein, or to form the shunt with a special terminal, in which case it is necessary to form a countersunk hole to take the special terminal and its gripping fastening.

In carrying out the method which results in the type of connection shown in Figs. 1 and 2 a cable or conductor 23 is secured to a brush 24 which may consist of carbon, mixture of carbon and copper, etc. The brush 24 is provided with a passage 25 and a passage 26 extending through the brush and intersecting the passage 25. The gripping member 27, best shown in Fig. 3, is formed of copper, brass or similar deformable conducting material in the shape of a spool having end portions 28, 28 connected by a neck portion 29. The gripping member 27 is placed in the passage 26 and an end of the conductor 23 is then inserted through the passage 25 into the passage 26 between the end portions 28, 28, after which the latter are forced together to grip the conductor end therebetween, flattening and spreading the conductor. The force employed may be such as to expand the end portions 28, 28 outwardly into contact with the wall of the passage 26, thus forming good electrical contact with the brush 24. However, this is not necessary, as in any event after the conductor has been secured in place by the gripping member 27, the connection and adjoining parts of the brush will be suitably copper coated and tinned, providing a firm mechanical connection having low electrical resistance.

The deformable gripping member may be of various sizes but should be large enough to permit of a groove that will give abutments of sufficient size to grip the cable and at the same time give ample strength in the neck portion 29. Should I so desire I may extend the passage 25 beyond the passage 26 as at 25' in which case there will be an undeformed portion 23' of the cable below the gripping member, thus more firmly securing the cable.

In Figs. 4 and 5, I show a rivet 31 and washer 32 which may replace the deformable gripping member 27. Where these members are used it is immaterial whether the cable 23 is inserted in the hole 25 before or after

the rivet and washer are inserted in the hole 26. It is, of course, understood that the cable 23 is gripped between a shoulder 33 of the rivet and an opposed face 34 of the washer 5 and that the rivet is afterwards expanded against the washer 32. In Figs. 6 and 7, I show a split rivet 35 and a suitable washer 36, this rivet and washer gripping the conductor 23 in the same manner as do the rivet 10 and washer 31 and 32. In Figs. 8 and 9, I show a rivet 37 and a washer 38, the washer 38 having an annular recess 39 therein. Upon forcing the rivet 37 against the washer 38 the thin wall 40 of the rivet is spread in the recess 39 thus gripping the cable 23. In Figs. 10 and 11, I show a rivet 41 and corresponding washer 42 which have slotted flanges, the flanges being so slotted in order to provide frictional contact with the walls of the passage 26. In all the four modifications last described it will be noted that the members are interlocked one with another and, although the members may engage the walls of the passage 26, I do not rely upon this engagement to hold the opposed abutments in contact with the cable 23 until the coppering and tinning takes place.

In Figs. 12 and 13, 14 and 15, and 16 and 17, I show types of gripping members in which the frictional contact of the gripping member upon the passage wall is relied upon to hold the gripping member against the cable until coppering and tinning occur. In Figs. 12 and 13, the members 43 and 44 are provided with flanges 45. These flanges have slots 46 whereby the flanges may be sprung outwardly against the wall thus holding the members in engagement with the cable 23. In Figs. 14 and 15 the cable gripping members 51 and 52 have grooves 53 on their opposing surfaces. In Figs. 16 and 17 one member 54 of the pair of gripping members has a projection 55 thereon which is designed to register with a recess 56 on the opposed member 57. It is designed that in this modification of my invention the cable shall pass across the center of the gripping members and be held in the recess 56.

In Figs. 18 and 19, I show another deformable gripping member, this member being like that shown in Fig. 3 except that it has a groove 57 on one side thereof instead of around the circumference of the cylinder as shown in Fig. 3.

All the above types of connections are best carried out where the passages 25 and 26 are holes drilled approximately at right angles to each other. However, it is possible

to carry out my invention in another modification which I have illustrated in Figs. 20, 21 and 22. In this modification a brush block 61 has a hole 62 drilled therethrough and a groove 63 is milled or otherwise formed in the face of the brush block opening into the end of the hole 62. The cable 23 is placed between the jaws 64 at one end of a gripping member 65 and the jaws are then deformed to grip the end of the cable, after which the gripping member 65 is forced into the hole 62 and the whole secured in the latter by coppering and tinning.

While I have shown my invention in numerous embodiments, it will be obvious to those skilled in the art that it is susceptible of various other changes and modifications without departing from the principles of the invention.

What I claim is:

1. A conducting body having intersecting passages therein, a conductor in one of said passages, means in the other passage for gripping said conductor, said gripping means comprising a single piece of deformable material having opposed abutments gripping said conductor therebetween. 80

2. A method of attaching conductors to rigid bodies which comprises forming intersecting passages in said body; placing a deformable member having spaced opposed abutments in one of said passages; inserting said conductor through the other of said passages into the first-mentioned passage, with a portion thereof between said abutments; and deforming said member whereby said conductor is gripped between said abutments. 90

3. A conducting body having a groove in one face thereof and a recess in said face communicating with said groove, a single gripping member in said recess, said gripping member having opposed abutments, a cable in said groove and between said abutments, said abutments gripping said cable. 100

4. A conducting body having a longitudinal passage and an opening intersecting said passage at an angle thereto, a conductor extending through said passage into said opening and gripping means in said opening, said gripping means having a portion of reduced cross section disposed opposite said passage, the non-reduced portions forming abutments for engagement with the conductor. 105

In testimony whereof, I affix my signature.

ALFRED G. PLIMMER.
